(57) **CLAIM**

I claim the ornamental design for an outer follower element for a high pressure seal, as shown and described.

DESCRIPTION

FIG. 1 is a perspective view of an outer follower element for a high pressure seal embodying the invention;

FIG. 2 is a top view of the outer follower element for a high pressure seal of FIG. 1;

FIG. 3 is a bottom view of the outer follower element for a high pressure seal of FIG. 1;

FIG. 4 is a left side view of the outer follower element for a high pressure seal of FIG. 1;

FIG. 5 is a right side view of the outer follower element for a high pressure seal of FIG. 1;

FIG. 6 is a rear view of the outer follower element for a high pressure seal of FIG. 1; and,

FIG. 7 is a front view of the outer follower element for a high pressure seal of FIG. 1.
